SPICE RACK

William C. Diesinger, Jr., 624 Morris Ave.,
Bryn Mawr, Pa.

Filed Nov. 18, 1964, Ser. No. 82,667

Term of patent 14 years

(Cl. D44—29)

FIG. 1.

FIG. 5.

FIG. 2.

FIG.6.

FIG.3.

FIG.4.

FIG. 1 is a perspective view from the bottom of a spice rack, showing my new design;

FIG. 2 is a top plan view of the spice rack of FIG. 1;
FIG. 3 is a front view of the spice rack of FIG. 1;
FIG. 4 is a bottom view of the spice rack of FIG. 1;
FIG. 5 is a rear view of the spice rack of FIG. 1; and
FIG. 6 is a side view of the spice rack of FIG. 1.

I claim:

The ornamental design of a spice rack, substantially as shown.
